CIGAR MACHINE LONG-FILLER FEED

Henry H. Wheeler, Brooklyn, N. Y., assignor to
International Cigar Machinery Company, a
corporation of New Jersey

Application November 14, 1939, Serial No. 304,299

52 Claims. (Cl. 131—21)

This invention relates to cigar machines and more particularly to long filler feeds for cigar machines, its main object being to so device the parts which feed and manipulate the tobacco to produce a more uniform and homogeneous bunch charge than has heretofore been possible.

Another object of the invention is to simplify the machine by constructing it with as few moving parts as possible. Thus it has been possible to build the machine with 25% fewer parts than the standard cigar machine equipped with the cross feed.

A further object of the invention is to drive the filler feed belts which intermittently forward the leaves laid in the channel formed by the belts through a roller clutch which has fewer parts than the pawl-and-ratchet mechanism now forming a part of the cross feed control and more accurately starts and stops the feeding of the filler stream. With a pawl-and-ratchet mechanism it will be evident that there will be lost motion occurring during the engagement of the ratchet with the pawl, and inaccuracies in starting and stopping inherent in its construction.

The filler stream is advanced by increments corresponding to the desired size of bunch length to be severed from the stream upon a lower corrugated cutter fastened to the adjacent end of a vertically movable platform. An upper corrugated cutter coacts with the lower cutter to sever successive bunch lengths with a zig-zag line of cut desirable for the provision of the proper amount of filler at the head and tuck ends of the bunch charges subsequently separated from the compacted bunch lengths. A movable compactor and the upper corrugated cutter clamp the section of the stream adjacent the platform and compact it sufficiently to mat the filler and thereby prevent crumbling thereof, particularly at the pointed sections at the zig-zag line of cut. This enhances the uniformity of the bunch lengths and moreover prevents dropping of tobacco particles through the lower corrugated knife on the platform.

A further object of the invention is to assemble and compact the severed bunch lengths in a vertical column from the top of which the bunch charges are separated for delivery to the bunch rolling mechanism. Thus the separated bunch charges may be transported rectilinearly and without disturbance to the bunch rolling mechanism while in the measuring pocket into which the column of tobacco is lifted and compacted prior to separation of the bunch charge. In prior constructions wherein the bunch charges are

separated from the bottom of a vertical column, they are removed by slides which necessitate additional moving parts and disturb the charges.

Another object of the invention is to provide an oscillatory knife having a serrated cutting edge and formed of sheet metal with a thickness such that it will not disturb the horizontal laminations or layers of tobacco in the column while it is being advanced through it. In prior constructions there have been provided separator plates supported vibratory knives on their forward edges, and the requisite greater thickness of the separator plate has disturbed the tobacco during the separation of a bunch charge. Moreover the tobacco wedges in the slot between the knife and the separator plate and further disturbs the laminations of the column. By advancing the knife lengthwise of the bunch lengths in the column for the separation of bunch charges as contemplated, the length of the machine may be shortened, which feature constitutes another object of the invention. Furthermore the knife closes the open bottom of the measuring pocket and serves to retain the separated bunch charge therein as the transfer is advanced across the knife, and the corrugated filler ends are not mutilated while cutting.

A further object of the invention is to support the surplus tobacco remaining in the column after a charge has been separated therefrom, until the next ascent of the platform with a bunch length whereby the surplus tobacco is elevated into the measuring pocket and re-compacted. The platform may be provided with slots admitting the members which serve to support the surplus tobacco during the descent of the platform, and said members may be supported on the carriage of the knife which separates the bunch charge, to reduce the number of moving parts.

Still another object is to provide an adjustable construction of the charge measuring pocket whereby the size of the charge may be conveniently and minutely varied with a single adjustment. To this end the pocket is equipped with a yielding plate which is urged downwardly by a compression spring and pushed upwardly by the column during the compaction thereof. A plunger on the plate is seated against a crown knob threaded on the pocket and provided with axial grooves with any one of which may be engaged a spring wire to maintain the knob in the adjusted position thereof for stopping the inward movement of the plunger with the plate and thereby controlling the size of the charge. The plat-

form supporting the column is urged upwardly by a tension spring connected thereto to compact the column to a predetermined density preparatory to the separation of a bunch charge.

To still further minimize the disturbance of the bunch charge, there may be provided a suction platform for raising a portion of the apron into contact with the open bottom of the measuring pocket for reception of the bunch charge, which is ejected by a spring-pressed plate within the measuring pocket, during the lowering of said portion of the apron. The platform may be perforated and connected to a source of suction to cause adherence of the apron thereto during its descent and thereby form a loop which is advanced by the rolling pin to roll the charge upon itself while on the platform and then within a binder on the bunch rolling table, and the corresponding portion of the apron may likewise be perforated to permit the charge to be suctionally retained thereon.

On the rolling pin is fastened a plate which is swung downwardly from a horizontal position wherein it supports the charge in the measuring pocket as the latter is slid thereover on to the elevated portion of the apron, to a position wherein it holds the charge against the apron while the bunch charge is being rolled upon itself. In prior constructions this plate was loosely pivoted on the rolling pin and swung down upon the charge during the forward movement of the rolling pin over the rolling table, but in the present arrangement it is swung down upon the charge prior to the forward movement of the rolling pin by a shaft which is geared to a cam-actuated rack and coupled with one end of the rolling pin during the return of the latter to initial position as the plate is swung back prior to rolling of the rolled charge within the binder spread upon the portion of the apron extending over the table the rolling pin is turned back into position to be coupled with said shaft upon return to its initial position.

The filler feed belts, which are driven through the roller clutch, may be set into operation by a trip which is actuated by the plunger carrying the compressor platform. In this event the clutch, which is later disengaged when the filler stream has been advanced an increment corresponding to the desired bunch length, is thrown out of operation by a stationary stop which is adjustable to permit the feed belts to be advanced by various increments corresponding to the various desired lengths of bunch. In the event there is an excess of tobacco in the column the trip will not be operated and the clutch will remain ineffective, until the height of the column has diminished to the proper level. Accordingly other objects of the invention are to provide a novel clutch construction, which is more efficient and may be adjusted for various bunch lengths, and to provide for controlling the same from the compactor plunger.

In the accompanying drawings which form a part of this specification and in which like characters of reference indicate the same or like parts:

Fig. 18 is a detail side elevation of the adjustable bearing supports for the rolling pin; and

Fig. 19 is a sectional plan view thereof.

Referring to Figs. 1, 2 and 3 of the drawings, the tobacco feed channel consists of a horizontal endless belt 15 running over pulleys 16, 17, 18 and 19, and of two vertical endless belts 20 and 21 running over pulleys 22, 23 and 24, 25, respectively. The horizontal pulley 16 is mounted on a shaft 26 which is adjustable by screws 27. The vertical pulleys 22 and 24 revolve on bolts 28 adjustable in slots 29. The pulley 18 is mounted on a shaft 30 and carries bevel gears 31 meshing with gears 32 on shafts 33 of pulleys 23 and 25 (Fig. 3). Shaft 30 is supported in bearings of a frame 34 attached to the bed 35 of the cigar machine and carries and has fastened thereon the housing 36 of a ratchet 37 having gear teeth 38 formed on its hub meshing with a rack 39 intermittently actuated by a rod 40 connected to a cam lever (not shown). With

ratchet 37 is associated a locking disk 41 having rollers 42, Figs. 4, 6 and 7, extending into the notches 43 of ratchet 37. Through a circular hole 44 in disk 41 passes the shank of an eccentric stud 45 whose head is free to turn in a slot 46 of ratchet 37 (Fig. 3). The portion of the

stud 45 within the slot 46 is eccentric with respect to the shank of the stud. A lever 47 fastened to the shank of the stud is equipped with a roller 48 on a stud 49 at its free end, a stop lug 471 at the other end of lever 47 being held in tension against the hub of disk 41 by a spring 52 anchored on a post 53 of disk 41. In this position the roller 48 is at rest above a finger 50 carried by an arm 51. When the arm 51 is tripped by the charge compressor, as will be hereinafter described, the finger 50 strikes the roller 48 causing the spring 52 to pull the same into the dotted position 48', thereby turning the eccentric stud 45 and moving its shank into dotted position 45'. This movement of stud 45 displaces the disk 41 in the counterclockwise direction, thereby wedging the pins 42 into locking contact with the ratchet 37 and housing 36, so that the ratchet will drive shaft 30 in the clockwise direction on the next downward stroke of rack 39. Near the end of that stroke, a nose 54 extending from lever 47, which is then in position 54', engages a pin 55 carried by a disk 56 adjustably attached by bolts passing through slots 57 thereof to frame 34 and set at the proper angular distance to terminate the advance of the tobacco layer T. As the rack then completes its stroke, the nose 54 in passing pin 55 turns the lever 47 back into its original position, disengaging the rollers 42 and resetting the disk 41 into non-driving position. A roller 58 carried by disk 41, near the end of the upward stroke of rack 39 engages the raised finger 50, thereby pushing the lever 51 back into its neutral position. The ratchet locking disk 41 and the throw-out disk 56 are enclosed by a guard 59 attached to frame 34.

The inlet end of the feed channel has a guard 60, and the delivery end is provided with a top guide 61, which compacts the tobacco upon the belt 15 and thereby prevents telescoping of adjoining sections of the tobacco stream thereon, and side guides 62 which aid in guiding the tobacco layer T on to the cutting platform. The vertical feed belts are protected by covers 63, and a leaf-handling table 64 is provided at one side of the feed channel for the convenience of the operator.

The cutting platform 65 forms the top of the compressor and bunch-length cutting unit shown in Figs. 8, 9 and 10. The platform 65, which is provided with longitudinal slots 66 and carries the corrugated knife 67, is mounted on the head 68 of a plunger 69 floating in a slide 70, the plunger and slide being connected by a tension spring 71. The slide 70 has a cover plate 72 and is moved up and down in a stationary slide bracket 73 by a cam-operated rod 74. The bracket 73 has pockets 75 connected with the suction system of the machine to carry off tobacco scrap and dust produced by compressing and cutting the charge.

The lower end of plunger 69 has a recess forming an oil reservoir 76 closed by a plug 77 and fillable through a covered opening 78 in slide cover plate 72 upon removing cover screw 79 (Fig. 10). Within the reservoir 76 there is a piston 80 suspended on a pin 81 in cover plate 72, this piston having a small bore 82 through which the oil is forced as the plunger 69 is moved up and through which it must return on the down stroke of the plunger, thereby providing a dash-pot effect cushioning the movement of the plunger relative to 70.

The tobacco layer T at each advance of the 75

feed belts is forwarded on the cutting platform 65 against a stationary slotted wall 83, Fig. 9. By adjusting this wall and the angular position of the resetting pin 55 relative to the movement of nose 54 the desired size of bunch length may be obtained. The platform 65 is then raised by the rod 74, thus forcing the knife 67 against a stationary knife 84, Figs. 1, 2 and 8, held by an arm 85 attached to frame 34, and thereby cutting the bunch length advanced thereon from the tobacco layer T. Near the end of the upward stroke of the plunger 69, a screw 86 carried by a projection 87 on the same engages with a pin 88, (Figs. 1, 2 and 8), extending from a pawl 89 held by a spring 90 against a trip lever 91 which in turn is held in tension by a spring 92. The lever 91 is clamped to a shaft 93 to which is also fixedly attached the arm 51 carrying the finger 50 which actuates the tobacco feed (Figs. 1, 4 and 8). Thus, when the lever 91 is tripped by the screw 86 against a stop screw 94, the shaft 93 turns the arm 51 and the finger 50 strikes the roller 48, thereby setting the rollers 42 of the feed clutch 37 into driving engagement so that tobacco is fed at the next cycle of the machine.

However, when the plunger 69 is prevented by a sufficient accumulation of tobacco on platform 65 from following the complete stroke of the slide 70, the motion of the plunger is terminated while the spring 71 stretches and the screw 86 will not engage the pin 88, so that in this case the feed clutch 37 remains inactive and no tobacco is fed during the next cycle.

Some distance above the stationary knife 84 is suspended the charge transfer pocket 95, Figs. 1, 9 and 12, which is provided with slides 96 and 97 and has a yielding wall 98 adjustable by means of nuts on suspension studs 99 and urged into its lowermost position by a compression spring seated in guide stud 100. The inward or upward movement of the wall 98 is limited by a crown-knob 101 threaded on the boss of the pocket 95 wherein the guide stud is mounted and engaging the upper end of said stud, whereby the thickness of the charge may be varied by turning said knob. This knob is kept from accidental turning by a spring wire 102 extending into its axial grooves. The slides 96 and 97 engage with stationary horizontal guide rails 103 and 104, the latter being made with a separate gib-rail 105 for convenience in assembling. The slide 97 is attached to one of the side plates 106 (Figs. 9 and 12) of an endless chain 107 running over sprockets 108 and 109. The sprocket 108 is mounted on a shaft 110 supported in a pedestal 111 (Figs. 1 and 12) and carrying a gear 112 meshing with a rack 113 connected by a link 114 to a cam lever 115. The rack 113 is guided by pedestal 111 and its cover 116, and is protected by a housing 117 attached to the top of the pedestal. The sprocket 109 is mounted on a shaft 118 carried by a bracket 119 adjustable on rail 104 by a set screw 120.

In a plane immediately below the transfer pocket 95 is disposed a horizontal knife blade 121 (Figs. 1, 9 and 12) formed of sheet metal, preferably steel, of sufficient thinness to separate the charge in the pocket from the column without disturbing the laminations of the latter, and supported on a bracket 122 attached to the top of a vertical shaft 123. This blade is provided with a scalloped or saw tooth cutting edge on its forward end and arranged to oscillate as it moves forward under the pocket lengthwise thereof to

sever the bunch charge therein from the top of the tobacco column raised by the cutting platform 65. The shaft 123, Figs. 1, 9 and 11, is supported in bearings 124 of a slide 125 held in grooves of a guide frame 126 by a gib-rail 127. On a stud 128 in slide 125 is pivoted a link 129 connected to a bell crank lever 130 turning on a stud 131 in the sub-frame 132 of the machine. This lever is actuated by a cam-operated rod 133 and produces the sliding motion of knife 121 whereby the latter is advanced forwardly through the tobacco column and then withdrawn after the pocket 95 has been moved thereover to charge delivery position.

Between the bearings 124 there is clamped to shaft 123 an arm 134 carrying a ball stud 135 connected by a ball screw 136 and nuts 137 to a link 138 carried on an eccentric shaft 139 between the forked hubs 140 of a bracket 141 attached to slide 125. The shaft 139 is supported by pedestals 142 of guide frame 126 and is intermittently driven by a pulley 143 connected by a belt 144 with a pulley 145 on a shaft 146 journaled in sub-frame 132 against a thrust bearing 147 (Fig. 9). The shaft 146 is driven through a clutch 148, Figs. 1 and 2, from a bevel gear 149 meshing with a bevel gear 150 on the main shaft 151 of the machine, the clutch 148 being actuated by the forks 152 of a cam lever 153 pivoted on a stud 154 and held by a spring 155 against a barrel cam 156 on cam shaft 157. The shaft 151 is at right angles to shaft 146 at the belt feed end of the machine and is supported by brackets 158 attached to the sub-frame 132.

The slide 125 at its forward end has a T-shaped vertical groove 159, Figs. 1 and 9, in which is slideable a holder 160 carrying a row of horizontal fingers 161 below the knife blade 121. This holder is equipped with a stud 162 supported in the slot of a horizontal rail 163 carried at the top end of a vertical plunger 164 slideable in a bracket 165 attached to base 35, and pivoted to a cam-operated rod 166. The fingers 161, besides partaking of the horizontal motion of the oscillating knife 121, thus also have a vertical motion controlled by a cam. The space between the cutting platform 65 and the transfer pocket 95 is enclosed by walls 167 and 168, Figs. 1 and 12, the front wall 167 being provided with a door 169, preferably made of transparent material and slideable by means of a knob 170 so as to give access to this chamber when required for cleaning.

The operation of the mechanisms thus far described is as follows, see Fig. 9:

I. With the cutting platform 65 in its lowermost position, the tobacco layer T is advanced onto the same by the feed belts across plate 255 whose inner end is cut away to fit the indentations of knife 67.

II. The cutting platform is raised into an intermediate position, thereby cutting off a bunch length from tobacco layer T thereon.

III. The fingers 161 are withdrawn from their inner position 161' in which they support the surplus tobacco from the preceding cycle, to their outer position 161'', thereby dropping this surplus tobacco on top of the cut bunch length on the cutting platform, thus forming a tobacco column T' on the same.

IV. Cutting platform 65 then completes its upward stroke, lifting column T' into pocket 95 and compressing same and thereby raising plate 98 into its top position which limits the thickness of charge T'' to be cut. Near the end of its upward stroke, the contact screw 86 on compressor

plunger 68 engages the pin 88 of the feed control, thereby setting the feed clutch into action for the next cycle.

V. Supporting fingers 161 move into up-position so as to register with the slots 66' in the raised cutting platform 65.

VI. Oscillating knife blade 121 moves forward to sever charge T'' in transfer pocket, the same movement also bringing the fingers 161 through the slots of wall 83 into position 161''' within the slots 66'.

VII. Cutting platform 65 returns to down-position, leaving the surplus tobacco T' on the interposed fingers 161'''.

VIII. Fingers 161''' with the surplus tobacco return to down-position 161', ready to add this tobacco to the new charge on the next up-move of the cutting platform. If at any time the accumulated tobacco column T' on the cutting platform is of sufficient magnitude to prevent the plunger 69 of the compressor from following the complete stroke of the slide 70, the contact screw 86 will not lift the pin 88, and the tobacco feed will remain inactive during the next cycle, causing the platform 65 to start its ascent empty and to bring into pocket 95 only the surplus tobacco T' left from the preceding cycle. While the compressor goes through its next cycle, the cut charge T'' in the transfer pocket 95 is carried to the rolling table and deposited thereon for rolling within a binder into a cigar bunch B' by the rolling apron.

On the base 35 is mounted a slotted block 171, Figs. 12 and 13, to which is attached the base 172 of the bunch rolling table 173 and which supports a slide 174 having guide rollers 175 engaging guide slots in the bottom of the base 172 as shown in Fig. 13. To slide 174 are fastened brackets 176 and 177 each carrying bearing supports 178 having fastened thereto a bearing 178a by a cap screw 178c passing through slot 178b, the bearings 178a having a bore receiving the trunnions 179 of the rolling pin 180. The bracket 177 has a ball stud 181 which, by a link 182, is connected to a cam lever 183. On the trunnions 179 are fixedly mounted brackets 184 to which is attached a rider plate 185 which, when in the innermost or starting position of the rolling pin, is turned in the bearings 178 by coupling a projecting flat 186 on the end of one of the trunnions 179 with a slot in a shaft 187 supported by a pedestal 188 (Figs. 1 and 13) and carrying a gear 189 meshing with a rack 190 connected by a link 191 with a cam lever 192 (Fig. 12). To one trunnion 179 is clamped a crank 193 at such an angle that after the plate 185 has been swung through an arc of 180° to dotted position 185' from the rest position of the rolling pin where the coupling engagement of members 186 and 187 takes place, the same is in position to subsequently engage with a stationary roller 194 carried by an arm 195 attached to pedestal 188, as shown in dotted lines at 193' in Fig. 12, corresponding to position 185'' of the rider plate. As the rolling pin then completes its travel over the rolling table, the crank 193' is turned back by the roller 194, thus restoring the plate 185 to its original position. One of the brackets 184 carries a set screw 196 (Fig. 12) which is adjusted to rest on a ledge 197 of bracket 177 when rider plate 185 is in line with the advancing tobacco charge T'.

On the base 172 (Figs. 12 and 13) are mounted pedestal brackets 198 and 199 carrying the shaft 200 of a drum 201 in a notch of which one end of the rolling apron 202 is fastened, the other end

being held by a clamp 203 to the outer end of rolling table 173. The shaft 200 carries a sprocket 204 which is intermittently driven by an endless chain 205. The pedestal 198 also has a bearing 206 in which is journaled a shaft 207 carrying at one end an arm 208 connected by a link 209 to lugs on the chamber 210 of a suction platform 211, Figs. 12 and 14. The chamber 210 is guided by a rod 212 fitting into the bore of a socket 213 extending from the base 172. Air is exhausted from the chamber 210 through a nipple 214 slideable in a socket 215 leading to a duct 216 in base 172, this duct communicating by a pipe 217 Fig. 13, attached to base 35, with a pipe 218 connected to the suction system of the machine which also exhausts the main chamber of base 172 through a pipe entering a hole 219, provided for this purpose. The platform 211 and the rolling table 173 have waste-collecting channels 220 formed by side rails 221 and 221a respectively (Figs. 1 and 14) attached to the same. On the other end of shaft 207 is mounted an arm 222 connected by a rod 223 to a cam lever 224.

The operation of the charge manipulating and rolling mechanism just described is as follows:

The charge T' is cut off the column T' by the oscillating knife 121 and the pocket 95 is carried by the chain 107 into the dotted position T' shown in Fig. 12, the charge being supported on the way by the rider plate 185, and at position T' the charge is received by the rolling apron 202 on suction platform 211 which has been raised into the dotted position 211' by the arm 208 during the travel of pocket 95. As the platform 211 then descends into the full line position, during which the perforated portion of the apron overlying it adheres thereon and forms a loop 202' in the rolling apron required for rolling the charge, the plate 185 is swung into position 185' by the rack 190, the plate thereby acting to hold down the charge while it is being rolled into the bunch charge T''' by the advance of the rolling pin 180 due to cam lever 183. While the plate 185 is being swung into position 185', the drum 201 is turned forward by the chain 205 to pass out a length of apron 202 sufficient for the loop 202'. In position 180' of the rolling pin, when the charge T''' has attained the bunch shape T''', the drum 201 turns backward to tighten the apron around the same, and the crank 193' engages the roller 194. While the rolling pin 180 is moving into position 180', a binder B has been deposited upon the rolling apron 202 on the table 173 by the suction head of a binder transfer (not shown). As the rolling pin then moves into its extreme position 180'', the charge T''' is rolled within the binder B thereby forming the bunch B' which, after being tightened by a final backward turn of the apron drum 201, is ready for delivery into a bunch transfer to be carried to the bunch shaping and wrapping mechanisms of the cigar machine.

In Figs. 15 to 17, a modification in the arrangement of the bunch length cutters and of the charge-compressor is shown. Here, the upper corrugated knife 84, instead of being stationary, is attached to a reciprocable bar 225 actuated by a rod 226 from a properly timed cam lever. The bar 225 carries a bracket 227 from which is suspended a pressure foot 228 resting on the tobacco layer T under the pressure of a spring 229. To this pressure foot is hinged the top guide 230 which is suspended from the bracket 227 by a link 231. As the upper knife 84 descends to-

wards the lower knife 67, the guide 230 depresses the incoming tobacco layer T and the foot 228 precompresses the same before entering the cutting platform 65. The latter is fastened on the plunger 232 which is moved up and down in bracket 73 by the rod 74 attached to cam lever 234 held in upward tension by a spring 235 attached to the base 35 of the machine. The plunger 232 on a suitable projection 233 carries the contact screw 87a which registers with pin 88 in pawl 89 of a control similar to that shown in Fig. 8 and similarly controls the action of the tobacco feed. The plunger has lugs 236 carrying set screws 237 which come to rest on a plate 238 attached to the base 35 and limit the movement of the compressor at the end of its stroke.

The cam lever 234, after raising the plunger 232 high enough for the knife 67 to engage with the knife 84 in cutting through the tobacco layer T, runs off its track on the cam, allowing the spring 235 to compress the tobacco column T on the platform 65 as it raises the same into the pocket 95. The plate 98 of the transfer pocket 95 is cut off flush with the end of knife 84 and a separate plate 239 having corrugations registering with those of the knife 84 is suspended on studs 240 from socket 241 provided on the pocket 95. The plate 239 is held in downward tension by a compression spring 242 and rests on the knife 84, except when the latter is in its lowermost position shown in Fig. 15, when the adjusting nuts on studs 240 hold it above the path of the oscillating charge-cutting knife 121 while the knife 84 has descended below knife 121 to its lowermost position limited by a stop screw 243 in frame 34. The plate 239 fits into the notches formed in the end of the incoming tobacco charge and thus prevents lateral shifting of the bunch charge layers during the cutting operation of the oscillating knife 121. A plate 244 attached to a recess in the top of arm 225 serves as a guide for the knife 121 when at its innermost position.

A plate 252 (Fig. 15) bridges the gap between the filler feeding belt and the platform, and its inner end is cut away to fit the indentations of the knife 67 and conform to the shape of the cutting edge of the knife 84. Thus the latter as it descends clamps the filler stream on the plate 252, so that the tobacco will be firmly held at this point while the platform ascends and causes the knife 67 to engage with the knife 84 for severing a bunch length.

The tension of the spring 235 may be regulated by turning the screw eye connecting it to the cam lever 234 (Fig. 16), whereby the density of the bunch charge may be varied, but ordinarily after the proper tension of the spring has been obtained it is not disturbed. With the form of construction shown in Figs. 15 and 16 there is no tendency for the compressor platform to be slammed against the column of tobacco following the cutting of a bunch charge and hence no dash-pot is needed.

In Fig. 1a there is shown a suitable form of two-way valve controlling the application of suction to the suction platform 211 and the pockets 75 for carrying off dust and scrap. As shown, a T or valve housing 245 has a socket fitting a pipe 246 leading to a suction fan (not shown) and also has one branch communicating with the pipe 218, which is connected to the pipe 217 leading to the suction chamber 210, and two other branches connected to the suction pockets 75. A valve plate 247 is pivotally mounted on a shaft 248 protruding from the valve housing and car-

rying an arm 249 connected by a rod 250 to a cam lever 251. The valve plate is normally maintained in a position closing the branch connected to the pipe 218 by a tension spring 252 connected to the cam lever 251, and the cam lever 251 is timed to swing the valve-plate into the dotted position and permit the suction to be applied to the suction platform 211 at the proper time, the suction meanwhile being cut off from the pipes 75.

To prevent accumulation of tobacco in the channels 221 of the bunch rolling table, there may be provided sweeps 253 carried by the brackets 176 and 177 of the rolling pin (Fig. 1b) and extending downwardly within the side walls 221 and into the channels. As the sweeps move toward the delivery end of the table they carry particles of tobacco which may escape from the bunch charge and lodge in the channels into the chute 254 connected to the suction system of the machine.

It may be noted that with the illustrated construction of the charge former the charge-cutting knife is of such thinness that it minimizes the production of scrap and will be moved more easily through the laminations of the compressed column of tobacco than constructions employing a thicker separator plate behind the cutter. Such separator plates tend to unduly compress the charge while separating it or tend to push back the compressor with the portion of the tobacco column behind the separator plate. The illustrated construction also permits the separation of charges from a column compacted to a greater degree. Occasionally a tobacco leaf section would lodge in the space between the separator plate and the knife and be pushed ahead, further disturbing the laminations of the tobacco column. As mentioned herein, by moving the charge-cutting knife lengthwise of the assembled bunch lengths their corrugated ends will not be mutilated or broken off as when the knife moves transversely of bunch lengths.

As shown in Figs. 18 and 19 each of the bearing supports 178 for the trunnions of the rolling pin is equipped with a bearing 178a which carries one of the trunnions and is provided with a slot 178b through which passes a cap screw 178c threaded into the support 178 and fastening the bearing 178a thereto. Upon loosening the screws 178c the bearings 178a may be raised or lowered to tilt the rolling pin from a horizontal position wherein it is adapted to coact with a straight table, to oppositely inclined positions wherein they are adapted to coact with right or left hand curved rolling tables. Each of the bearings 178 has a stem clamped in its respective bracket whereby the bracket may be turned to suit the various tilted positions of the rolling pin.

Following an adjustment of the trunnion bearing supports the shaft 187 should be raised or lowered to admit the flattened trunnion end 186 at the various adjusted positions thereof. For this purpose the pedestal 188 is equipped with a vertically adjustable bearing bracket 188a which carries the shaft 187 and is fastened to the pedestal 188 by a cap screw passing through an elongated slot permitting requisite vertical adjustment of the shaft upon loosening the cap screw.

What is claimed is:

1. In a cigar machine, the combination with a vertically movable platform, of means for intermittently advancing a continuous stream of tobacco on to said platform, cutters coacting to sever from the remainder of the filler stream the

section of the filler stream advanced on to said platform, a measuring pocket overlying said platform, mechanism for raising said platform to elevate the severed tobacco section into said measuring pocket and thereby fill said pocket with a charge of tobacco and compact the same therein, and a device for separating the charge filling said pocket from the remainder of the compacted tobacco in the section.

2. In a cigar machine, the combination with a vertically movable platform, of means for intermittently advancing a continuous stream of tobacco on to said platform, cutters coacting to sever from the remainder of the filler stream the section of the filler stream advanced on to said platform, a measuring pocket overlying said platform, mechanism for raising said platform to elevate the severed tobacco section into said measuring pocket and thereby fill said pocket with a charge of tobacco and compact the same therein, a device separating the charge filling said pocket from the remainder of the compacted tobacco section, and members for supporting the surplus tobacco remaining after separation of said charge during the descent of said platform whereby it may be recompacted in said measuring pocket during the next ascent of said platform.

3. In a cigar machine, the combination with a vertically movable platform, of means for intermittently advancing a continuous stream of tobacco on to said platform, cutters coacting to sever from the remainder of the filler stream the section of the filler stream advanced on to said platform, a measuring pocket overlying said platform, mechanism for raising said platform to elevate the severed tobacco section into said measuring pocket and thereby fill said pocket with a charge of tobacco and compact the same therein, a device separating the charge filling said pocket from the remainder of the compacted tobacco section, and members for supporting the surplus tobacco remaining after separation of said charge during the descent of said platform whereby it may be recompacted in said measuring pocket during the next ascent of said platform, said platform having slots in its upper face, and said members being movable into said slots to underlie the tobacco supported on said platform and support the surplus tobacco during the descent of the platform.

4. In a cigar machine, the combination with a vertically movable platform, of means for intermittently advancing a continuous stream of tobacco on to said platform, a pair of cutters coacting to sever from the remainder of the filler stream the section of the filler stream advanced on to said platform, a measuring pocket overlying said platform, mechanism for raising said platform to elevate the severed tobacco section into said measuring pocket and thereby fill said pocket with a charge of tobacco and compact the same therein, a device separating the charge filling said pocket from the remainder of the compacted tobacco in said section, one of said cutters being fastened to said platform and movable therewith, and the other cutter being stationary and disposed in a position above the platform to cause the tobacco section to be separated during the ascent of said platform.

5. In a cigar machine, the combination with a vertically movable platform, of means for intermittently advancing a continuous stream of filler tobacco on to said platform, an upper cutter and a lower cutter coacting to sever from the remainder of the filler stream bunch lengths

advanced on to said platform, said cutters having corrugated cutting edges forming indentations in the ends of the severed bunch lengths, a plate bridging the gap between said means and platform and having a corrugated configuration at its end adjacent the platform conforming to the configuration of the cutting edge of the upper cutter, said lower cutter being fastened to said platform and movable therewith and the upper cutter being movable downwardly to clamp the tobacco stream upon the corrugated end of said plate prior to the ascent of said platform and coat with said lower cutter in severing a bunch length during the ascent of said platform, and mechanism for raising said platform to cause severing of the bunch lengths and elevation thereof.

6. In a cigar machine, the combination with a vertically movable platform, of means for intermittently advancing a continuous stream of tobacco on to said platform, an upper and a lower cutter coacting to sever from the remainder of the stream a bunch length advanced on to said platform and having corrugated cutting edges forming indentations in the ends of the severed bunch lengths, a measuring pocket overlying said platform, mechanism for raising said platform to elevate the severed bunch length into said measuring pocket and thereby fill said pocket with a charge of tobacco and compact the same therein, and a device separating the charge filling said pocket from the remainder of the compacted tobacco in said bunch length, said measuring pocket having a plate provided with a configuration interfitting the indentations in the underlying end of the charge in said pocket to prevent shifting thereof during the cutting of said charge.

7. In a cigar machine, the combination with a vertically movable platform, of means for intermittently advancing a continuous stream of tobacco on to said platform, cutters coacting to sever from the remainder of the filler stream the section of the filler stream advanced on to said platform, a measuring pocket overlying said platform, mechanism for raising said platform to elevate the severed tobacco section into said measuring pocket and thereby fill said pocket with a charge of tobacco and compact the same therein, and a device separating the charge filling said pocket from the remainder of the compacted tobacco section, said measuring pocket having a yielding plate adapted to eject the separated charge and an adjustable stop for limiting the yielding movement of said plate, and said mechanism for elevating the platform being yieldable to compact the tobacco to a predetermined density.

8. In a cigar machine, the combination with a vertically movable platform adapted to elevate a severed tobacco portion, of means for intermittently advancing a continuous stream of tobacco on to said platform, a downwardly moving cutter adapted to sever the portion of the filler stream advanced on to said platform, a measuring pocket overlying said platform to admit the tobacco portion severed by said cutter and elevated by said platform, and a compactor connected to said cutter for compressing the tobacco stream at a portion in front of said platform.

9. In a cigar machine, the combination with a vertically movable platform, of means for intermittently advancing a continuous stream of tobacco on to said platform, cutters coacting

to sever from the remainder of the filler stream the portion of the filler stream advanced on to said platform, an abutment overlying said platform, mechanism for raising said platform to elevate and compact the severed tobacco portion against said abutment, a device for separating a bunch charge from the compacted tobacco portion, and members for supporting the surplus tobacco remaining after separation of said charge during the descent of said platform whereby it may be recompacted during the next ascent of said platform.

10. The combination with a vertical measuring pocket, of a vertically movable platform adapted to support and elevate a tobacco section into said pocket and thereby fill the pocket with a charge and compact the same therein, a vibratory knife for separating the charge filling said pocket from the remainder of the compacted tobacco section, and mechanism for moving said pocket rectilinearly to transfer the separated charge.

11. The combination with members adapted to confine a vertical column of tobacco, of a horizontal oscillatory knife adapted to be moved horizontally through a vertical column of tobacco confined within said members and separate a charge from the top of said column, and mechanism for actuating said knife.

12. The combination with a vertically movable platform, of means for intermittently advancing a continuous stream of tobacco on to said platform, a cutter acting to sever from the remainder of the filler stream the portion of the filler stream advanced on to said platform, mechanism for elevating the platform with the tobacco portion severed by said cutter thereon, and a compactor actuated by said cutter for compressing the tobacco stream at a portion in front of said platform.

13. The combination with a rolling apron having a perforated charge receiving portion, a movable perforated platform underlying said apron and having a suction chamber communicating through the perforations of said platform with the perforations of the charge receiving apron portion to suctionally retain a bunch charge deposited thereon, and mechanism for elevating said platform with the overlying apron portion to receive a charge and then lowering said platform with the charge and the portion of the rolling apron adhering thereto to form a loop in the apron.

14. The combination with a cigar bunch charge transfer having an open bottom, of a rolling apron having a charge receiving portion, mechanism for moving said charge transfer into position to deposit a bunch charge upon the charge receiving portion of said apron, a movable perforated platform underlying said apron and having a suction chamber communicating through the perforations of said platform with the bottom of said charge receiving apron portion, mechanism for elevating said platform to raise the charge receiving apron portion into position to engage the open bottom of said charge transfer to receive the charge from said transfer and then lowering said platform with the charge and the portion of the rolling apron adhering thereto to form a loop in the apron, and a rolling pin movable to and fro across said platform to carry said loop forwardly thereover and roll the charge upon itself.

15. In a cigar machine, the combination with a vertically movable platform, of means for intermittently advancing a continuous stream of to-

bacco on to said platform, cutters coacting to sever from the remainder of the filler stream the portion of the filler stream advanced on to said platform, a measuring pocket overlying said platform, mechanism for raising said platform to elevate the tobacco portion severed by said cutters into said measuring pocket and thereby fill said pocket with a charge and compact the same therein, a horizontal knife for separating the charge filling said pocket from the remainder of the compacted tobacco portion, and means for moving said measuring pocket with the charge rectilinearly.

16. In a cigar machine, the combination with a vertically movable platform, of means for intermittently advancing a continuous stream of tobacco on to said platform, cutters coacting to sever from the remainder of the filler stream the portion of the filler stream advanced on to said platform, a measuring pocket overlying said platform, mechanism for raising said platform to elevate the tobacco portion severed by said cutters into said measuring pocket and thereby fill said pocket with a charge and compact the same therein, a horizontal knife for separating the charge filling said pocket from the remainder of the compacted tobacco portion, and means for moving said measuring pocket with the charge rectilinearly across the upper face of said knife whereby the charge is retained in said pocket by the knife while being removed from the said tobacco portion.

17. The combination with a bunch rolling table, a bunch rolling apron extending across said table and arranged to receive a bunch charge at one portion thereof and receive a binder at another portion thereof, a rolling pin movable to and fro to cause said rolling pin to roll the bunch charge upon itself and then roll it within said binder to form a bunch, a plate supported on said pin and projecting forwardly thereof, and mechanism for positively swinging said plate downwardly to press upon the charge while it is being rolled upon itself and then swinging said plate upwardly while it is being rolled within the binder.

18. In a cigar machine, the combination with a vertically movable platform, of means for intermittently advancing a continuous stream of tobacco on to said platform, cutters co-acting to sever from the remainder of the filler stream the section of the filler stream advanced on to said platform, a measuring pocket overlying said platform, mechanism for raising said platform to elevate the tobacco section severed by said cutters into said measuring pocket and thereby fill said pocket with a charge and compact the same therein and subsequently lowering the platform to return it to initial position, a horizontal knife, means for moving said knife to and fro across said tobacco section for separating the charge filling said pocket from the remainder of the compacted tobacco in said tobacco section, and members for supporting the surplus tobacco remaining after separation of said charge during the descent of said platform whereby it may be recompacted in said measuring pocket during the next ascent of said platform, said platform being provided with slots in its upper face, and said members being supported by said means for moving the knife, for movement into said slots during the movement of the knife through the tobacco section whereby the surplus tobacco will be supported by said members during the descent of said platform.

19. The combination with a vertically movable platform adapted to support a tobacco section, of means for intermittently raising said platform to elevate the tobacco section and subsequently lowering the platform to return it to initial position, said platform having slots in its upper face, members movable into said slots for supporting the tobacco section elevated on said platform, during the descent of the latter, and mechanism for intermittently moving said members into said slots.

20. The combination with a vertically movable platform adapted to support a tobacco section, of means for intermittently raising said platform to elevate the tobacco section and subsequently lowering the platform to initial position, said platform having slots in its upper face, members movable into said slots for supporting the tobacco on said platform during the descent of the latter, and mechanism for intermittently moving said members into said slots while the platform is elevated and then lowering the members with the tobacco supported thereon and finally retracting the members.

21. The combination with a vertical measuring pocket, of a platform adapted to elevate a tobacco section into said pocket and compact the same therein, a vertically movable plunger supporting said platform, a vertically movable slide, mechanism for raising and lowering said slide, and a tension spring connecting said slide to said plunger whereby the tobacco section is elevated by said platform into said pocket and compacted therein to a predetermined density.

22. The combination with a vertical measuring pocket, of a platform adapted to elevate a tobacco section into said pocket and compact the same therein, a vertically movable plunger supporting said platform, a vertically movable slide, mechanism for raising and lowering said slide, a spring connecting said slide to said plunger whereby the tobacco section is elevated by said platform into said pocket and compacted therein to a predetermined density, an oil reservoir in the lower end of said plunger, and a perforated piston mounted in said reservoir and connected to said slide whereby oil is forced through said piston during movement of said slide relative to said plunger.

23. The combination with a slide, of means for longitudinally reciprocating said slide, a horizontal vibratory knife mounted on a vertical axis on said slide, a shaft extending longitudinally of said slide, a crank mounted on said shaft and connected to said knife for imparting vibratory movement thereto, a counter shaft mounted externally of said slide and connected to and driving the shaft on which said crank is mounted, and a cam-actuated clutch on said counter shaft for intermittently driving the same.

24. The combination with a vertical bunch charge measuring pocket having an open bottom through which a tobacco charge may be inserted, an endless chain connected to said pocket, and means for driving said chain to transfer said pocket with the inserted charge to delivery position.

25. The combination with a bunch rolling apron having a loop therein and adapted to support a bunch charge, of supporting members movable along said apron, a rolling pin having trunnions mounted in said members and adapted to roll the bunch charge upon itself within said loop, a plate mounted on said trunnions, a shaft

adapted to be coupled with one of said trunnions, and means for turning said shaft to swing said plate downwardly into a position projecting forwardly of the rolling pin to hold the charge down upon the apron while rolling it upon itself.

26. The combination with a bunch rolling table having waste collecting channels, of members projecting into said channels, mechanism for traversing said members along said channels to remove tobacco particles therefrom, and a chute arranged to receive the tobacco particles from said members.

27. The combination with means for assembling tobacco sections to form a vertical column, of a horizontal knife arranged to separate a charge from the top of said column, and means for moving said knife through said column to separate a charge from the top of said column.

28. The combination with a vertical measuring pocket having an open bottom, of means for elevating a vertical column of tobacco into said pocket to compact the same, a horizontal knife for separating the charge filling said pocket from the remainder of the compacted tobacco in said column, said knife having an area coextensive with the open bottom of said pocket, means for moving said pocket with the separated charge to a delivery position, and means for moving said knife through said column to separate the charge in said pocket and close the open bottom thereof while the charge is being advanced to delivery position.

29. In a cigar machine, the combination with a vertically movable platform, of means for intermittently advancing a continuous stream of tobacco on to said platform, cutters coacting to sever from the remainder of the filler stream the section of the filler stream advanced on to said platform, an abutment overlying said platform, mechanism for raising said platform to elevate and compact the severed section against said abutment, a device for separating a bunch charge from the remainder of the compacted tobacco section, said means being controlled by said mechanism and incapacitated therefrom when there is sufficient surplus tobacco remaining to form additional charges, and members for supporting the surplus tobacco remaining after separation of said charge during the next ascent of said platform.

30. The combination with a measuring pocket, of a movable member adapted to advance a tobacco section into said pocket and compact the same therein, said pocket being provided with a yielding abutment adapted to be displaced inwardly in the pocket and to eject the inserted tobacco and an adjustable stop arranged to engage said abutment when it is displaced inwardly for limiting the inward yielding movement of said abutment, and yielding means for actuating said member whereby the tobacco is compacted to a predetermined density against said abutment.

31. The combination with a vertical measuring pocket, of a vertically movable platform adapted to elevate a tobacco section into said pocket and compact the same therein, said pocket being provided with a yielding plate disposed to engage the inserted portion of the tobacco section, and yielding means for elevating said platform whereby the tobacco is compacted to a predetermined density.

32. The combination with a vertically movable platform adapted to support a tobacco section,

of means for intermittently raising said platform to elevate the tobacco section and subsequently lowering the platform to return it to initial position, said platform having slots in its upper face, and members adapted to enter said slots for supporting the tobacco section on said platform during the descent of the latter.

33. In a cigar machine, a column forming receptacle for holding cigar filler tobacco in a vertical column, and means for periodically adding increments of tobacco to the bottom of a column of tobacco in said receptacle, said means including a plurality of relatively movable elements each adapted to support said column, mechanism for separating said elements while one of the elements supports the column, means for introducing an increment of tobacco into the space below the last mentioned column supporting element and above the other element, and mechanism for withdrawing said one element and supporting the combined column and increment on the other of said elements.

34. In a cigar machine, a column forming receptacle for confining tobacco in a vertical column, mechanism for periodically adding increments of tobacco to the bottom of a column of tobacco in said receptacle, and means for separating measured bunch charges from the upper end of said column, said mechanism including a member having a horizontal face arranged to engage and support the bottom of the column, and means for actuating said member to elevate the column into position for separation of a bunch charge from its upper end.

35. In a cigar machine, a column forming receptacle for confining tobacco in a vertical column, mechanism for periodically adding increments of tobacco to the bottom of a column of tobacco in said receptacle, means for separating a measured bunch charge from the upper end of said column; said means including a measuring element having a flat horizontal surface arranged to overlie said column, devices exerting a predetermined pressure upwardly from the bottom of said column, and charge separating mechanism for separating a predetermined volume from the upper end of said column while under said pressure.

36. In a cigar machine, spaced vertical walls for holding a vertical column of tobacco, mechanism including a presser for exerting a predetermined pressure on one end of a vertical column of tobacco held by said walls, measuring mechanism for measuring and separating a charge of tobacco from the other end of said column while under said pressure, spacing means for periodically relatively moving said presser and column of tobacco away from one another to provide a space between them, and a tobacco feed for feeding an increment of tobacco into said space after relative movement of said presser and column away from each other.

37. In a cigar machine, spaced vertical walls for holding a vertical column of tobacco, mechanism including a presser for exerting a predetermined pressure on one end of a vertical column of tobacco held by said walls, measuring mechanism for measuring and separating a charge of tobacco from the other end of said column while under said pressure, spacing means for periodically relatively moving said presser and column of tobacco away from one another to provide a space between them, and a tobacco feed for feeding an increment of tobacco into said space after relative movement of said presser

and column away from each other, said spacing means including a column holder movable relative to said presser to hold the end of the column adjacent said presser after relative movement of said presser and column away from each other.

38. In a cigar machine, spaced vertical walls for holding a vertical column of tobacco, mechanism including a presser for exerting a predetermined pressure on one end of a vertical column of tobacco held by said walls, measuring mechanism for measuring and separating a charge of tobacco from the other end of said column while under said pressure, spacing means for periodically relatively moving said presser and column of tobacco away from one another to provide a space between them, and a tobacco feed for feeding an increment of tobacco into said space after relative movement of said presser and column away from each other and means for withdrawing said spacing means from between the column and the presser after the increment has been fed into said space.

39. In a cigar machine, the combination with a bunch rolling apron, a vertically movable platform adapted to elevate said apron to charge-receiving position, the top of said platform being perforated and the platform being equipped with a suction chamber communicating with said perforations, and means for intermittently applying suction to said chamber.

40. The combination with a measuring pocket arranged to admit a column of bunch lengths having corrugated ends, of means for advancing a column of bunch lengths having corrugated ends into said pocket and compacting the same therein, a knife separating the charge filling said pocket from the remainder of the compacted column, and a plate within said measuring pocket having a configuration fitting the indentations in one end of the charge filling said pocket to prevent shifting thereof during cutting of said tobacco layer.

41. The combination with a member for simultaneously elevating a tobacco section and compacting the same to a predetermined density, of means for separating a bunch charge from the top of a tobacco section elevated by said member while it is compacted by said member, and a device for supporting the surplus tobacco remaining in said section after separation of the bunch charge, until the next section has been elevated by said member whereby the surplus tobacco will be compacted by the section elevated by said member.

42. In a cigar machine, the combination with means for assembling tobacco sections in a vertical column and compacting the column to a predetermined density, of mechanism for separating bunch charges from the top of a vertical column of tobacco sections assembled by said means and transferring them horizontally to bunch rolling position.

43. The combination with mechanism for compacting a column of laminated layers of long filler tobacco, a knife of sufficient thinness to separate a bunch charge from a column of laminated layers of long filler tobacco compacted by said mechanism without substantially disturbing the laminations thereof, mechanism for supporting and vibrating said knife about an axis disposed externally of said column, and means for moving said mechanism to advance the vibrating knife through the compacted column to separate a bunch charge therefrom.

44. The combination with a knife adapted to

be moved horizontally into a compacted column of laminated layers of long filler tobacco to sever a charge therefrom, of a movable support whereon said knife is pivotally mounted for oscillatory movement, means for moving said support to cause said knife to move into said column and then withdraw therefrom, and mechanism for oscillating said knife while it enters said column and interrupting the oscillation of said knife.

45. In a cigar machine, a filler feeding channel for advancing a continuous layer of tobacco, means for compacting the continuous layer of tobacco advanced in said channel, said means having a vertically movable cutter plate, a movable support forming a continuation of said channel, a knife mounted on said support, means for moving said support vertically upward to cause said knife to sever bunch lengths of tobacco from said layer of tobacco, said several means being constructed and arranged to constitute mechanism for forming a bunch length of tobacco upon said support, and mechanism for separating a bunch charge of tobacco from a bunch length formed on said support.

46. The combination with a filler feeding channel for advancing a continuous layer of tobacco, and means for compacting the continuous layer of tobacco advanced in said channel, of a knife constructed and arranged to bear against the top face of said layer, a vertically movable support arranged to engage the opposite face of said stream, a cutter located on said support, means to raise said support and cause said cutter to sever bunch lengths of tobacco from said stream, and means to transfer each bunch, so formed, as a unit for further operations in the fabrication of cigars, successively, said knife and cutter having interfitting corrugated cutting edges coacting with each other to sever a bunch length having pig-tails on its ends during the ascent of said support.

47. In a cigar machine, the combination with mechanism for confining a plurality of layers of long filler tobacco cut to bunch lengths in a vertical column, of means for feeding long filler tobacco layer by layer into the range of action of said confining means, means for severing bunch charges from a vertical column of a plurality of tobacco layers of long filler bunch lengths confined by said mechanism, including a reciprocating support and a knife mounted thereon, means for moving said knife at right angles to the vertical axis of said column to cut said charges therefrom while maintaining the arrangement of said layers undisturbed, and means for oscillating said knife in its plane of movement during the charge cutting operation thereof to separate a charge from the column and reduce the cutting of tobacco to a minimum.

48. The combination with a yieldingly mounted movable abutment, of an adjustable member arranged to engage said abutment as it yields for limiting the yielding movement thereof, and a yielding device for advancing a column of tobacco vertically against said abutment to compact the tobacco in said column to a predetermined density, the yielding compacting force of said device being adjustable.

49. The combination with a yieldingly mounted movable abutment, of an adjustable member arranged to engage said abutment as it yields for limiting the yielding movement thereof, a yielding device for advancing a column of tobacco vertically against said abutment to compact the tobacco in said column to a predetermined density.

mined density, the yielding compacting force of said device being adjustable, and a knife for separating a bunch charge from the remainder of the column of tobacco compacted between said abutment and device.

50. The combination with a charge measuring pocket having a yielding abutment movable inwardly into the pocket and a member arranged to engage said abutment as it is moved inwardly and limit its inward movement, said member being adjustable to vary the extent to which the abutment may be displaced inwardly into the pocket and thereby vary the capacity of the pocket, a yielding device for advancing a column of tobacco into said pocket and against said abutment to displace the latter inwardly into the pocket, the yielding compacting force of said device being adjustable, a knife for separating a bunch charge in said pocket from the compacted column of tobacco, and mechanism for transferring said pocket with the separated bunch charge therein to delivery position.

51. In a cigar machine, the combination with

5 a filler tobacco feeding channel and means for compacting said tobacco therein to form a continuous layer of substantially uniform density, of a floating compressing member, a support forming a continuation of said channel and acting in opposition to said member, mechanism for forming a laminated vertical column of tobacco cut to bunch lengths between said member and said support, including means tending to impart the desired density to said column, and a cutter for separating bunch charges from said column of tobacco.

10 52. In a cigar machine, the combination with a tobacco feeding channel and means for compacting said tobacco therein to form a continuous layer of substantially uniform density, of a floating yieldably mounted compressing member, and a vertically movable support forming a horizontal continuation of said channel and acting in opposition to said member and coacting therewith to compact the tobacco.

HENRY H. WHEELER.
